US00D904448S

(12) **United States Design Patent** (10) Patent No.: **US D904,448 S**
(45) Date of Patent: **** Dec. 8, 2020**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Patrick Lee Coffman**, San Francisco, CA (US); **Woon Yung Choi**, Sunnyvale, CA (US); **Maxwell O. Drukman**, San Francisco, CA (US); **Peter Walter Roman**, Los Altos, CA (US); **Chun Kin Minor Wong**, Cupertino, CA (US)

(73) Assignee: **Apple Inc.**, Cupertino, CA (US)

(**) Term: **15 Years**

(21) Appl. No.: **29/746,415**

(22) Filed: **Aug. 13, 2020**
